APPARATUS FOR EQUALIZING TENSION IN ELASTIC RIBBON

Philip L. Jarvis, Pawtucket, R. I., assignor to Jarvis Mfg. Corp., Pawtucket, R. I., a corporation of Rhode Island

Application July 19, 1955, Serial No. 523,033

7 Claims. (Cl. 242—153)

This invention is directed to a method and apparatus for applying a uniform tension to relatively narrow elastic ribbon material.

With more specificity my invention is directed to apparatus through which relatively narrow elastic ribbon stock is passed as it is led to a braiding machine, covering machine or a winding and reeling point such that a desired uniform tension is applied and the ribbon leaves the apparatus with a uniform tension.

One of the objects of my invention is to lead elastic ribbon stock over a plurality of equal diameter pulleys to even out the tension therein and to reverse the direction of ribbon travel between pulleys, to pass the ribbon over an enlarged diameter pulley, thence reversing the direction of travel of the ribbon and passing it over a plurality of friction surface pulleys having a diameter intermediate the first-mentioned pulleys and the enlarged diameter.

Another object of my invention is to provide a plurality of interconnected pulleys on a common axis wherein a first group of the pulleys to which an elastic ribbon is led have the smallest diameter, the intermediate pulley of said pulleys having the greatest diameter, and the last pulleys over which the ribbon is led having a diameter in between the smallest and the largest diameter pulleys along with reversing means positioned in spaced relation adjacent the pulleys and over which the ribbon is led to reverse its general direction as it passes from one pulley to the next pulley and wherein brake means are provided for limiting the rate of rotation of said pulleys over which said ribbon is pulled.

A further object of my invention is to provide a tension apparatus as just above described in which the pulleys have anti-friction surfaces over which the ribbon travels so that any relative movement, if any, between ribbon and that anti-friction surface is minimized.

A still further object of my invention is to provide a method of evening out the tension in a relatively narrow elastic ribbon by first applying a slight tension thereon and subsequently relaxing the relatively great tension to a tension application intermediate the first applied and the relatively great applied tensions.

Still further objects and the entire scope of applicability of the present invention will become apparent from the detailed description given hereinafter; it should be understood, however, that the detailed description and specific example given by way of illustration only and, while indicating preferred embodiment of the invention, is not given by way of limitation, since various changes and modifications within the spirit and scope of the invention will become apparent to those skilled in the art from this detailed description.

For a more complete understanding of the nature and scope of my invention, reference may be had to the drawings in which:

Fig. 1 is a perspective view of my tensioning apparatus showing the path of travel of an elastic ribbon therethrough;

2

Fig. 2 is a plan view of my tensioning apparatus; Fig. 3 is a front elevation of the tensioning apparatus as viewed from the bottom of Fig. 2; and

Fig. 4 is a sectional view of the composite pulleys along line 4—4 of Fig. 2.

Throughout the description like reference characters refer to similar elements.

In Fig. 1 the tensioning apparatus is generally indicated at 10 and a relatively narrow elastic ribbon is led from a supply spool F supported on a vertically extending spindle 11. The apparatus is built up about a frame generally indicated at 11 having an angle iron member 12 positioned horizontally and with a portion of one web, the upper web, as indicated at 13, bent up at a right angle and provided with aperture 13' to receive bolts or rivets and secure it to a post 15. The vertically extending web 12' of the angle iron 12 is apertured at one end thereof to receive a bolt 16 which is secured thereto by lock nuts 17 and 18, see Fig. 4.

Still continuing with the description of the frame 12, a depending bracket 19 having an up-turned end 19' is attached to the lower edge of vertical flange 12' opposite to the apertured end as by welding. At the opposite end from angle iron 12 from bracket 19 and the vertical flange 12' is attached a right angle bracket 20 having an up-turned end 20' which is attached to the vertical flange 12' of angle iron 12 as by welding or the whole frame may be cut out and bent up from a single piece of stock.

Bracket 20 has its extreme outer end bent at right angles as at 20" and is apertured to receive a bolt 21 which serves as an axle mounting for a pulley 22, to be described later.

Mounted on bolt 16 is an integrally formed plurality of pulleys generally indicated at 24 having the right-handed pulley 25 thereof, see Fig. 4, provided with groove 25' therein which receives a belt or strap 26 that supports a weight 27, see Fig. 1, so as to provide a friction brake or drag for the plurality of pulleys generally indicated at 24. Next adjacent to the left of pulley 25 are two of the

smallest diameter pulleys 28 and 29 having equal diameters, such pulleys being the first pulleys of the group of pulleys 24 to which the elastic ribbon R is led in its passage through the uniform tensioning applying apparatus.

Next adjacent to the left of pulleys 28 and 29 is a middle pulley 30 having a diameter which is the greatest diameter of all of the pulleys and next adjacent this pulley 30 are the last pulleys 31 and 32 having a diameter intermediate the diameter of the smallest pulleys 28 and 29 and the largest pulley 30. Each of the pulleys 31 and 32 are provided with friction surfacing 33, see Fig. 2, consisting of a strip of cork or other like material so as to provide for minimum slippage of the elastic ribbon when passing thereover.

Associated with each of the pulleys is a reversing means for the ribbon consisting of spaced apart upstanding posts 34-38, inclusive, about which the ribbon R is led from off one pulley and onto the next pulley there adjacent such that the general direction of the ribbon travel is reversed. These posts 34-38 extend upwardly from the bracket 19 and are generally perpendicular to a plane (not shown) containing the bracket 19 and extending below the bolt 16 mounting the plurality of integrally connected pulleys 24.

Referring to Figs. 2 and 3, it will be noted that pulley 22 supported by bracket 20 is in alignment with the last pulley 32 over which the ribbon travels in its transit through the tension applying apparatus. Pulley 32 is an idling pulley and is merely a guide pulley under which the ribbon R is led as shown in Fig. 1 as it leaves the apparatus and passes to the braiding point, covering machine or winding and reeling point.

In the specific example here illustrated pulleys 28 and

29. the smallest pulleys, or the first pulleys, have a diameter of 2 inches, pulley 30 has a diameter of $2\frac{3}{4}$ inches. Considering the pulley 30 having a diameter represented by 100%, pulleys 28 and 29 have a diameter of approximately 72.7% of the largest pulley while the intermediate pulleys 31 and 32 have a diameter of approximately 90.8% of pulley 30. The width of the pulley surface in each of the pulleys is here illustrated as being about $\frac{7}{16}$ ", and these pulleys easily accommodate elastic ribbons having a very narrow width up to a larger width substantially the width of the pulley surface. It will be noted in the transit of the ribbon R over the pulleys and the reversing means, namely, the posts 34-38, that the ribbon R passes adjacent the right of post 34 over pulley 28, see Fig. 2, over post 35 and then over pulley 29 and likewise over post 36, pulley 30, post 37, pulley 31, post 38, and the last pulley 32 to the underneath surface of pulley 23.

In carrying out this uniform tensioning of the ribbon R it will be noted that the ribbon transits two small diameter pulleys, and the tension therein is more or less relaxed. On leaving the post following the small pulleys, namely, the post 36, the ribbon is passed over the largest diameter pulley where it is stretched or placed under greater tension and thence it is led over post 37 and to the intermediate diameter pulleys 31 and 32 whose surfaces 33 have the friction whereby the ribbon has little, if any, slippage when transiting these pulleys 31 and 32 and thus on relaxing the tension from the stretching pulley 30 while passing over the last pulleys 31 and 32, the tension is evened out and the ribbon leaves the pulley 32 with uniform tension. Just why this phenomenon takes place is not fully understood, but by this combination of relationship of diameters of the plurality of pulleys over which the elastic ribbon is pulled in combination with the reversing means, such as the posts 34-38, and the braking means on the pulleys, the ribbon is given a uniform tension.

While I have disclosed a brake means consisting of the drag belt 26 and the weight 27 suspended therefrom to apply a drag on the pulley 25 and in turn the integrally connected other pulleys, this can be accomplished by other means (not shown) such as a spring applying pressure to the end of the pulleys or by a mere tangential drag applied to the pulleys.

This apparatus and method of evening out the tension in elastic ribbon to render it more workable for braiding, covering or even reeling has proved to be highly successful yet just what the explanation is as to why it so successfully applies an even tension is not fully understood. Progressive steps of applying tension to elastic ribbon are known in the prior art but evening out on a first set of pulleys, applying a relatively great tension and following the relaxing of the great tension by an intermediate application of tension seems to accomplish the desired result.

I claim as my invention:

1. Apparatus for applying a uniform tension to a relatively narrow band of elastic ribbon material which comprises a support frame, a plurality of parallel adjacent interconnected pulleys for rotation at the same speed mounted on said frame on a common axis and over which said ribbon is led from a supply to a take off point and means associated with said frame and positioned in spaced relation to said pulleys and over which said ribbon is led from off one pulley onto the one next adjacent to reverse the general direction of travel of the ribbon, the first two of said pulleys to which the ribbon is applied to condition it with a uniform tension therein being equal and having the smallest diameter of the pulleys, the pulley next adjacent to the second pulley having the greatest diameter, and the last two pulleys having equal

diameters intermediate the smallest and greatest diameters of the pulleys and provided with friction surfaces over which said ribbon is led to thereby provide a minimum of relative movement between ribbon and pulley surface and means for applying a braking drag to said plurality of interconnected pulleys.

2. Apparatus for applying a uniform tension to a relatively narrow band of elastic ribbon material which comprises a support frame, a plurality of parallel adjacent interconnected pulleys for rotation at the same speed mounted on said frame on a common axis and over which said ribbon is led from a supply to a take off point and means associated with said frame and positioned in spaced relation to said pulleys and over which said ribbon is led from off one pulley onto the one next adjacent to reverse the general direction of travel of the ribbon, the first pulley to which the ribbon is applied to condition it having the smallest diameter of the pulleys, the pulley next adjacent to the first pulley having the greatest diameter and the last pulley having a diameter intermediate the diameters of the smallest and largest pulleys, and means for applying a braking drag to said plurality of interconnected pulleys.

3. Apparatus of the character described in claim 2 wherein said last pulley has a friction surface thereon over which said ribbon is led to thereby provide a minimum of relative movement or slippage between ribbon and the surface of that pulley.

4. Apparatus for applying a uniform tension to a relatively narrow band of elastic ribbon material which comprises a support frame, a plurality of parallel adjacent interconnected pulleys for rotation at the same speed mounted on said frame on a common axis and over which said ribbon is led from a supply to a take off point and reversing means associated with said frame and positioned in spaced relation to said pulleys and over which said ribbon is led from off one pulley onto the one next adjacent to reverse the general direction of travel of the ribbon, said intermediate pulley having the largest diameter, the first pulleys to which the ribbon is led onto the apparatus having equal diameters of about 72% of the diameter of the intermediate pulley and the last pulley over which the ribbon is led on leaving the apparatus having a diameter of about 90% of the diameter of said intermediate pulley, said last pulleys over which the ribbon is led on leaving the apparatus having friction surfaces whereby a minimum of slippage occurs between the ribbon and their surfaces and means for applying a braking drag to said plurality of interconnected pulleys.

5. Apparatus of the character described in claim 4 wherein said first pulleys comprise two pulleys and said last pulleys comprise two pulleys and said reversing means for reversing the general direction of ribbon travel between pulleys comprises a fixed post about which said ribbon is led.

6. Apparatus of the character described in claim 5 wherein said brake means comprises a pulley affixed to said other pulleys and on the common axis therewith and having a strap led thereover and suspending a weight therefrom to afford a braking drag to the rotation of said pulleys.

7. Apparatus of the character described in claim 6 including a guide ribbon pulley on said frame in line with the last pulley over which said ribbon is led as it leaves said apparatus and positioned on the opposite side of said plurality of pulleys from said reverse means.
